ABRASIVE ARTICLE

John P. Fenton, Boston, Mass., assignor to
 American Sandpaper Company, a corporation
 of Massachusetts

Application May 1, 1941, Serial No. 391,303

3 Claims. (Cl. 51—185)

The invention relates to an abrasive article essentially adaptable for grinding and finishing, by power drive, generally concaved or irregular surfaces such as holes and channels in metal, or composition parts, including oil reservoirs in steel forgings; also irregularly concaved surfaces such as occur in castings and compression molded parts; likewise the removal of scale, grime, and waste from such concavities.

Such grinding and finishing has heretofore been only imperfectly possible, and at great expense of time and material, by the use of such tools as shaped abrasive stone, buffs using abrasive compounds, and hand work with coated abrasive sheets. Solid abrasive shapes are undesirable for the work for the reason that the hardness of the tool will not allow it to grind or finish smoothly, but rather causes violent short strokes which beat upon the work and result in imperfect finish, and cause what is known as "chatter marks." The solid abrasive tool after a short time so wears down as to lose its shape, and consequently can no longer be used for the desired purpose. Attempts to provide resiliency in these shapes so as to overcome chatter, by making a bond between the abrasive grains of some compressible material, such as rubber, have been unsuccessful because such bond will not grip the abrasive grain sufficiently, and loose grains from the tool are ground into the work, causing grooves and scratches. Buffs using abrasive compounds either grind loose grains against the work in a similar manner, or are too fine in their finishing action to perform satisfactorily in a reasonable length of time. Hand work is so slow as to be usually impractical because of cost, and frequently holes or depressions are too small to permit successful finishing by hand.

The object of my invention is to provide an abrasive tool capable of producing an improved quality of work under the circumstances above outlined, and to obviate the difficulties referred to.

The invention comprises an abrasive article of replaceable character applicable to a mandrel upon which it may be mounted, and to which it may be secured so as to be rotated by the mandrel as the mandrel is rotated. The abrasive article is one in which the coated abrasive material is pre-formed in its fore part to have a generally convex form with vaulted interior, and this is so supported that it may be mounted upon the mandrel which will afford a resilient backing therefor, especially to the vaulted interior of the convex part of the article; and to which mandrel

the abrasive article is securely bound so as to be rotated thereby as the mandrel is rotated. The article is also one so fitted as to be capable of eliminating grindings or dust from any hole or opening within which it may be working. These, together with other features of the invention, can best be seen and understood by reference to the drawing, in which

Fig. 1 is a side elevation of the abrasive article mounted upon a mandrel.

Fig. 2 is a longitudinal section of that shown in Fig. 1.

Fig. 3 is an end elevation thereof.

Fig. 4 is a plan of the abrasive material which forms an essential part of the article, after it has been cut, or died out, and prior to its being formed, or molded, into the shape it assumes in the completed article.

Fig. 5 is a modification in the cut of the abrasive material shown in Fig. 4; and

Fig. 6 is a side elevation of the completed abrasive article when made from abrasive material with cut as shown in Fig. 5.

Fig. 7 shows in cross section a slightly modified structure.

The abrasive article comprises various elements including a disk 1, arms 2 extending from said disk, and an internal sleeve 3 over which the arms are extended and to which the arms are secured.

The disk 1 is a generally round, relatively flat, though preferably slightly convexed piece. It forms the fore end of the article, and is located centrally with relation to its axis. The arms 2 are preferably spaced arms. They extend from all around the edges of the disk, first with an outward broad convexity which gives to the fore part of the article its generally convex form and vaulted interior. After reaching the point where the arms impart to the article its full diametric size, the arms extend with a generally tubular extension substantially parallel with the axis of the article, which extension is continued onto the internal sleeve 3, to the exterior of which the arms are secured. The sleeve thus occupies a slight inward extension, commensurate with the thickness of the material from which the sleeve is made, from the annular plane within which those portions of the arms secured to the sleeve are lying. As previously explained, the arms are preferably spaced arms, and the spacing is continued over the exterior of the sleeve.

The disk and arms are cut or died out from a blank or sheet of a flexible coated abrasive material, preferably such as a strong but flexible

abrasive cloth; or coated abrasive which has a cloth backing. When cut or died out the disk and arms have the general form in the flat as shown in Fig. 4 where it will be seen that the arms radiate from the edges of the central disk. The arms are then given the desired convex shape, without overlapping, and held in that shape by bonding to the sleeve 3. The shaping is done by any suitable pre-forming device, or mechanism.

The sleeve 3 may be made of any suitable material provided it has the requisite inherent strength to withstand the strain to which it is subjected. A sleeve formed of paper, or cardboard, as known to those skilled in the art, is found in practice to be a suitable sleeve.

The abrasive is secured to its backing, and the arms to the sleeve, by a strong adhesive which will withstand a high degree of heat. Some of the known heat treated resinous adhesives are found in practice to be best for the purpose.

The abrasive article is rotated by mounting upon a rubber mandrel 5, or one composed of such material as will provide a proper support for the article and resilient backing therefor. The mandrel is so formed that the abrasive article will fit over it, with the end of the mandrel fashioned to fill the vaulted interior of the article. The mandrel is then expanded in such manner that the whole abrasive article will fit snugly thereon, although the strain induced by the expansion of the mandrel, for holding the article in place, is more or less concentrated upon the sleeve 3, thus relieving the arms of excessive strain, but providing them, especially those portions of the arms lying between the sleeve and the disk 1, with a firm, though resilient, backing.

Inasmuch as the abrasive surface material is securely bonded to its backing there is no tendency for the abrasive grains to pry loose. Since the abrasive coat is only one layer thick there can be practically no loss of shape in use; as soon as the abrasive article placed upon the rubber mandrel is worn out it is replaced with a new abrasive article.

The abrasive article will operate successfully at either high or low speed, and will withstand most severe abuse as may be encountered in any finish grinding with abrasives, as in the finishing of oil well bearing holes in the steel propeller hubs of air planes. Since the abrasive article is flexible in itself, and while at work is backed by a resilient mandrel, it is able to hug the surface being abraded, or finished, without chatter.

During the operation of the abrasive article the grindings, together with bits of worn abrasive, and dust, will be forced out of the concavity or groove within which the article is working, escaping by way of the spaces between the arms 2. These spaces form grooves 6 which provide a free outlet for such material as the grooves are devoid of abrasive material.

In connection with these grooves 6, obtained

by spacing the arms, a further refinement is shown in Figs. 5 and 6, in that the grooves, instead of being substantially parallel to the axis of the article, are made, through the initial cutting or dieing out of the arms, to occupy an angular position with relation to the axis. These angular cut grooves better free themselves of the material to be ejected by the centrifugal action which arises, as the article is rotated.

10 In Fig. 7 a slightly modified structure of the abrasive article is shown in that the sleeve 3 is extended into the vaulted end of the article by a part 3' which assists in further reinforcing the arms 2, the spacing 6 between the arms being maintained the same as before.

I claim:

1. An abrasive article comprising a flexible abrasive material fashioned to form an end piece centrally disposed with arms projecting from and around said end piece and convexed to impart a general convexity to said abrasive article in the part thereof bounded by the convexity in said arms and to which said end piece forms an apex, an interior sleeve over which said arms are extended whereby the abrading working surface thereof will be increased, and to which sleeve said arms are adhesively secured whereby they are retained and reinforced by the sleeve, said sleeve providing a bearing against which an interior mandrel may be expanded for holding said abrasive article in place during its rotation.

2. An abrasive article comprising a flexible abrasive material fashioned to form an end piece centrally disposed with arms projecting from and around said end piece and convexed to impart a general convexity to said abrasive article in the part thereof bounded by the convexity in said arms and to which said end piece forms an apex, an interior sleeve over which said arms have a generally tubular extension and to which sleeve said arms are adhesively secured whereby they are retained and reinforced by the sleeve, said sleeve providing a bearing against which an interior mandrel may be expanded for holding said abrasive article in place during its rotation.

3. An abrasive article comprising a flexible abrasive material fashioned to form an end piece centrally disposed with arms projecting from and around said end piece and convexed to impart a general convexity to said abrasive article in the part thereof bounded by the convexity in said arms and to which said end piece forms an apex, said arms having a generally tubular portion beyond the convexed portion thereof, a sleeve located inside said generally tubular portion of said arms with extension into the vaulted interior of the convexed portion thereof, and to which sleeve and extension said arms are adhesively secured whereby they are retained and reinforced thereby, said sleeve providing a bearing against which an interior mandrel may be extended for holding said abrasive article in place during its rotation.

JOHN P. FENTON.
